(57) **CLAIM**

I claim the ornamental design for a retractable shelf, as shown and described.

DESCRIPTION

FIG. 1 is a front, top, left side perspective view of a retractable shelf, showing my new design;

FIG. 2 is a rear, top, left side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front elevational view thereof in which the retractable shelf is in an expanded state;

FIG. 10 is a front elevational view thereof showing another configuration of use in which the retractable shelf is in another expanded state; and,

FIG. 11 is a front, top, left side perspective view thereof.

FIG. 5 of the retractable shelf includes the trademark "X folder" owned by the applicant, Gio Huh. The trademark is shown in broken lines and forms no part of the claimed design.

Further, a portion of the disclosure of this patent document contains material to which is subject to trademark protection. The trademark owner has no objection to the facsimile reproduction by anyone of the patent document or the patent disclosure, as it appears in the Patent and Trademark Office patent file or records, but reserves all other trademark whatsoever.
